Primary Examiner — Darcey E Gottschalk*(74) Attorney, Agent, or Firm* — Ann K. Gallagher(57) **CLAIM**

The ornamental design for an elbow support, as shown and described.

DESCRIPTION

FIG. 1 is a perspective view of an elbow support showing the new design;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The portions of the elbow support in FIGS. 1-7 shown in broken lines are included to show features that form no part of the claimed design. In addition, the dot-dash-dot type broken lines shown in the drawing views define the boundaries of the claimed design and form no part of the claimed design.
